UNITED STATES PATENT OFFICE.

JAMES R. COLLINS, OF DETROIT, MICHIGAN.

ICE-CREAM MEASURE.

1,372,863.

Specification of Letters Patent. Patented Mar. 29, 1921.

Application filed September 19, 1919. Serial No. 324,949.

To all whom it may concern:

Be it known that I, JAMES R. COLLINS, a citizen of the United States of America, residing at Detroit, in the county of Wayne 5 and State of Michigan, have invented certain new and useful Improvements in Ice-Cream Measures, of which the following is a specification, reference being had therein to the accompanying drawings.

10 This invention relates to ice cream measures, and more particularly to measures for facilitating the introduction of ice cream into cartons.

It is the object of the invention to provide an ice cream measure proportioned to snugly receive a carton in which the ice cream is to be dispensed and to provide the measure with a detachable rim for shielding the edge of the carton so as to permit 15 the latter to be filled by thrusting the measure into a body of ice cream.

A further object is to provide upon said detachable rim a scraping member, which when the measure is rotated manually will 20 dislodge the ice cream adhering to that within the measure.

A preferred embodiment of the invention is illustrated in the accompanying drawings wherein:

25 Figure 1 is a perspective view of the measure and its detachable rim, shown separated;

30 Fig. 2 is a sectional view of the upper portion of the measure showing a carton 35 therein and the detachable rim in its position of use.

In these views the reference character A designates an open-topped receptacle of inverted frusto-conical shape, the bottom of 40 said receptacle having the handle member B projecting centrally therefrom. At C is indicated a carton formed of card board or similar material and adapted to fit snugly within the receptacle A with its 45 rim portion projecting slightly therefrom. To retain said carton in the receptacle and to prevent its rim portion being crushed or bent when the carton is being filled by thrusting the receptacle within a body of 50 ice cream, there is employed a rim member D detachably engageable with the receptacle preferably by the bayonet joint established by the pin E on the receptacle and slot F formed in said rim member. The 55 outer marginal portion of the member D is inwardly return-bent as indicated at G

and overlaps the carton so as to shield the edge thereof when said rim member is in place upon the receptacle. At opposed points the flange G is interrupted to accommodate the end of a cutter H extending diametrically across the rim member D and rigidly secured thereto in the plane of its outer edge.

In the use of the described invention, 65 after a carton C has been placed in the receptacle A, the rim member D is applied to said receptacle and is given a slight turn to properly engage the bayonet slot F with the pin E. Holding the device by the handle B the operator then fills the carton C by plunging the measure while inverted into a body of ice cream. While still engaged with said body, the measure is turned slightly on its central axis, whereby the 70 blade H scrapes off any ice cream exteriorly adhering to that within the measure. The rim member D is then detached and the filled carton C is removed from the receptacle.

As compared to filling ice cream cartons by hand, the above described device accomplishes a very considerable saving of time and permits the ice cream to be packed into a carton more uniformly and to be scraped off more smoothly than is practicable with the means now employed.

What I claim as my invention is:

1. In a device of the character described, the combination with a receptacle for an 90 ice cream carton, of a rim member detachably engaging said receptacle and providing a shield for the edge of a carton within the receptacle, and means carried by said rim member for cutting off the ice cream 95 adhering to that filling the carton when the receptacle is rotated.

2. In a device of the character described, the combination with a receptacle for an ice cream carton, of a rim member detachably engaging said receptacle and providing a shield for the edge of a carton within the receptacle, and a cutter blade carried by said rim member in diametrical relation thereto.

3. In a device of the character described, the combination with a receptacle for an ice cream carton, of a rim member detachably engaging said receptacle and providing a shield for a carton within the receptacle, and a cutter blade carried by said rim member in diametrical relation thereto and

having its outer edge flush with that of said rim member.

4. In a device of the character described, the combination with a receptacle for an ice cream carton, of an annular rim member, having quick detachable telescoping engagement with said receptacle and having its outer edge portion inwardly return bent to shield the edge of the carton within

said receptacle, and a cutter blade diametrically carried by said rim member and having its outer edge substantially flush with that of said rim member, the shield portion of the rim being interrupted to permit attachment of said cutter blade to the body of the rim.

In testimony whereof I affix my signature.

JAMES R. COLLINS.
